C. H. LAY.
RAILWAY SIGNALING SYSTEM.
FILED JULY 28, 1920.

2 SHEETS-SHEET 2

UNITED STATES PATENT OFFICE.

CHARLES H. LAY, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING SYSTEM.

Application filed July 28, 1920. Serial No. 399,516.

To all whom it may concern:

Be it known that CHARLES H. LAY, a citizen of the United States, residing at Pittsburgh, in the county of Allegheny and State 5 of Pennsylvania, has invented certain new and useful Improvements in Railway Signaling Systems, of which the following is a specification.

My invention relates to railway signaling systems, and has for an object the provision of a novel and improved signaling system for single track railways over which traffic moves in both directions.

I will describe one form of railway signaling system embodying my invention, and will then point out the novel features thereof in claims.

In the accompanying drawings, Figs. 1 and 1^A are diagrammatic views showing one 20 form of signaling system embodying my invention, it being understood that a complete unit of the system is formed by placing these views end to end with the right hand end of Fig. 1 contiguous to the left hand end of 25 Fig. 1^A.

Referring now to the drawings, the reference characters 1 and 1^A designate the track rails of a stretch of single track between two passing sidings F and G. These 30 rails are divided by insulated joints 2 to form a plurality of sections A—B, B—C, C—D and D—E, these sections being further divided by insulated joints 2 to form sub-sections such as A—K and K—B. Each 35 sub-section is provided with a track circuit comprising a track battery b, the rails of the section, and a track relay designated by the reference character T, with a suitable exponent.

40 Traffic along the stretch A—E from west to east is governed by a plurality of roadside signals S¹, S², S³, and S⁷, while traffic along the stretch in the opposite direction is governed by a plurality of signals S², S⁴, 45 S⁶ and S⁸. As here shown, each of these signals is of the semaphore type, arranged to indicate stop, caution or proceed, according as the semaphore is in the horizontal, the inclined or the vertical position.

50 Each signal is controlled by a signal relay which is designated by the reference character R with the same exponent as that of the corresponding signal. Each of these

relays is of the polarized type, that is, responsive to the polarity of the current supplied thereto, and each signal is provided with a caution circuit and a proceed circuit, one or the other of which is closed according as the relay is energized in the reverse or the normal direction. 55

Considering signal S², the caution indication circuit is from the left hand terminal of battery H^E, through wires 4 and 5, contact 6 of signal relay R², wire 7, operating mechanism of signal S², wire 8, contact 9 of relay R², and wires 10 and 11 to the right hand terminal of battery H^E. This circuit is closed when relay R² is energized in either direction. The proceed indication circuit 60 for signal S² is from the left hand terminal of battery H^E, through wires 4 and 12, polar contact 13 of relay R², wires 14 and 15, contact 16 of relay R², wire 17, operating mechanism of signal S², and thence as before to the right hand terminal of battery H^E. 65 This proceed indication circuit is closed only when contact 13 is closed and contact 13 is closed only when relay R² is energized by current of normal polarity. 70

The caution and proceed circuits for signal S¹ are similar to those just traced for signal S², and will be understood without detailed explanation. 80

The caution circuit for signal S⁷ is from the right hand terminal of battery H^G, 85 through contact 200 of relay R⁷, operating mechanism of signal S⁷, and contact 201 of relay R⁷ to the left hand terminal of battery H^G. The proceed circuit for this signal is from the right hand terminal of battery H^G through contacts 200 and 202 of relay R⁷, operating mechanism of signal S⁷, 90 and contact 201 of relay R⁷ to the left hand terminal of battery H^G.

The control circuits for signal S⁸ are similar to those just traced for signal S⁷. 95

Considering now signal S⁴, the caution indication circuit is from the left hand terminal of battery H^D, through wires 18, 19, 20 and 21, contact 22 of signal relay R⁴, wires 100 23 and 24, contact 25 of track relay T⁷, wires 26 and 27, operating mechanism of signal S⁴, wires 28 and 29, contact 30 of relay R⁴, and wires 31, 32 and 154 to the right hand terminal of battery H^D. The proceed indication circuit for this signal is the same as 105

the caution indication circuit up to and including wire 26, and it then passes through wire 33, polar contact 34 of relay R^4 , wire 35, operating mechanism of signal S^4 , and 5 thence through the same path as the caution indication circuit to the right hand terminal of battery H^D . It will be observed that both circuits for signal S^4 include contact 25 of track relay T^7 , which is the track relay for 10 the first track circuit in advance of this signal. The reason for including this track relay contact in the circuits for signal S^4 will be explained hereinafter.

The caution and proceed circuits for signals 15 S^6 , S^3 and S^5 are similar to those just traced for signal S^4 . That is, signal S^6 is controlled by signal relay R^6 and by contact 164 of track relay T^3 , this track relay being associated with the first track circuit in advance 20 of the signal. Signal S^3 is controlled by signal relay R^3 and by track relay T^4 for sub-section B—N, while signal S^5 is controlled by signal relay R^5 and by track relay T^6 for sub-section C—U, each of these sub- 25 sections being the first one in advance of the corresponding signal. The reason for including a track relay contact in the control circuits for each of these signals will appear hereinafter.

30 The control of signal relay R^2 is as follows: This relay is provided with a main circuit which passes from the left hand terminal of battery H^d , through wires 18, 19, 20 and 21, front contact 22 of relay R^4 , 35 wires 23 and 36, right hand arm of pole-changer P^4 operated by signal S^4 , wire 37, contact 38 of track relay T^8 , wire 39, contact 40 of track relay T^9 , wire 41, winding of relay R^2 , wires 42 and 43, resistance 57, 40 right hand or normal point of polar contact 44 of relay R^2 , wires 45, 46, 47, 48, 49, common wire O' , and wires 49^a and 50, left hand arm of pole-changer P^4 , wires 51 and 29, contact 30 of signal relay R^4 , and 45 wires 31, 32 and 154 to the right hand terminal of battery H^d . When signal S^4 is in the proceed or the caution position, pole-changer P^4 is in what I will term the "normal" position wherein current of normal 50 polarity is supplied to relay R^2 , so that, assuming that the circuit for this relay is closed at all other points, the relay is energized in normal direction and signal S^2 indicates proceed. When signal S^4 indicates stop, however, it reverses the pole-changer P^4 , so that current of reverse 55 polarity is supplied to relay R^2 from battery H^d and signal S^2 then indicates caution.

The main circuit for relay R^2 is provided 60 with a branch around the right hand or normal point of polar contact 44, which branch passes from resistance 57, through the left hand or reverse point of polar contact 44, wires 52 and 53, battery H^c , and 65 wire 54 to wire 49. When relay R^2 is ener-

gized in the reverse direction this branch is closed so that relay R^2 is supplied with current from batteries H^c and H^D in series, and the two batteries then assist each other in energizing the relay in reverse direction. 70

When signal relay R^4 is open, battery H^D is disconnected from the main circuit of relay R^2 and this circuit is closed at relay R^4 . The circuit for relay R^2 then passes from wire 39, through track relay contact 75 38, wire 37, right hand arm of pole-changer P^4 (which is then reversed), resistance 203, wire 29, back point of contact 22 of relay R^4 , wires 23 and 36, left hand arm of pole-changer P^4 , wire 50, etc. If relay R^2 is 80 energized in the reverse direction at the time that relay R^4 opens, relay R^2 will continue to be energized in this direction by battery H^c , which is then in the circuit for the latter relay. If, however, relay R^2 is 85 in the normal direction when relay R^4 opens, relay R^2 will become de-energized, owing to the fact that there is no battey in the circuit of this relay.

The main circuit for relay R^2 is provided 90 with a third branch which passes from wire 42, through the back contact 55 of relay R^2 , and wire 58 to wire 47. Assuming that relays R^4 and R^2 are both de-energized and that relay R^4 then becomes energized, it is 95 apparent that relay R^2 will be supplied with current from battery H^D , through the branch just referred to, and so the latter relay will become energized.

Signal relay R^4 is provided with a main 100 circuit which passes from the left hand terminal of battery H^B , through wires 59, 60 and 61, left hand arm of pole-changer P^6 , wire 62, contact 63 of signal relay R^6 , wire 64, normal polar contact of signal relay R^6 , wire 66, contact 67 of track relay T^4 , wire 68, contact 69 of track relay T^5 , wire 70, contact 71 of track relay T^6 , wire 72, front point of contact 73 of track relay T^7 , wire 74, winding of relay R^4 , wire 75, front 110 point of contact 76 of track relay T^7 , wire 77, resistance 57^a, normal point of polar contact 78 of relay R^4 , wires 79, 80, common wire O , wires 80^a 151 and 152 right hand arm of pole-changer P^6 , and wires 81 and 82 to the 115 right hand terminal of battery H^B . This circuit is provided with a branch around the normal point of polar contact 78, which branch passes from resistance 57^a through the reverse point of polar contact 78, wire 120 153, wire 18, battery H^D , wires 154 and 155, reverse point of polar contact 156, and wire 157 to wire 80. The circuit for relay R^4 is provided with another branch which passes from wire 77, through wire 204, back contact 125 158 of signal relay R^4 , and wire 205, to wire 157. When signal relay R^6 is open, the circuit for relay R^4 is disconnected from battery H^B , and is closed at location B in the same manner as pointed out hereinbe- 130

fore in connection with the circuit for relay R^2 . That is, the circuit then passes from wire 64 through back point of contact 63 of relay R^6 , and wire 206 to wire 80.

5 The signal relay R^4 is provided with an auxiliary or local circuit which is at times supplied with current from battery H^P . Assuming that a train moving toward the west passes signal S^4 and that this signal 10 is in the proceed or caution position, the opening of track relay T^7 will close the following circuit for relay R^4 : from the left hand terminal of battery H^P , through wires 18, 19, 20 and 83, contact J^4 operated by signal S^4 , wires 84 and 85, back point of track relay contact 73, wire 74, winding of relay R^4 , wire 75, back point of track relay contact 76, and wires 86, 32 and 154 to the right hand terminal of battery H^P . After 15 contact J^4 opens, due to the movement of signal S^4 to the stop position, relay R^4 will continue to be energized as long as track relay T^7 remains open, because the local circuit for relay R^4 is provided with a 20 branch around contact J^4 , which branch passes from wire 19, through wire 87, contact 159 of relay R^4 and wire 88 to wire 85. As soon as the westbound train passes point U, track relay T^7 will again close, thereby 25 opening the local circuit for relay R^4 , and this relay will then become de-energized because its main circuit is opened at contact 71 of track relay T^6 . When an eastbound train enters sub-section U—D, the 30 local circuit for relay R^4 will not be closed because both contacts J^4 and 159 were previously opened due to the opening of the main circuit for relay R^4 .

In order to facilitate the explanation of 35 the control of relay R^6 , I will first explain the manner in which relay R^8 is controlled. The circuit for relay R^8 is (see right hand end of Fig. 1^A) from right hand terminal of battery H^G , through wires 53, 119, 120, 40 121 and 122, left hand arm of pole-changer P^2 , wire 123, contact 124 of track relay T^9 , wire 125, contact 126 of track relay T^{10} , wire 127 (now referring to left hand end of Fig. 1), contact 128 of track relay T^9 , wire 45 160, winding of relay R^8 , wires 129 and 130, common wire O^2 , (again referring to right hand end of Fig. 1^A), wires 130^a and 131, right hand arm of pole-changer P^2 , and wires 132, 133, 46, 47, 48 and 54 to the left 50 hand terminal of battery H^G . It will be seen from the foregoing that relay R^8 is de-energized while there is a train at any point between A in Fig. 1 and Q in Fig. 1^A, (assuming that the left-hand end of Fig. 1 55 is placed adjacent to the right-hand end of Fig. 1^A). It will be seen, furthermore, that if there is no train within these limits, relay R^8 will be energized in normal or reverse direction according to the position of signal S^2 . That is, relay R^8 will be ener-

gized in normal direction when signal S^2 is at proceed or caution, and in reverse direction when signal S^2 is at stop.

The circuit for signal relay R^6 is controlled by a pole-changer P^{90} or by a pole-changer P^{15} , according as a stick relay M^8 is open or closed. Relay M^8 is provided with a pick-up circuit which passes from battery H^F , through wires 134, 135, 136, 137 and 138, contact J^8 operated by signal S^8 , 75 wire 139, back contact 140 of track relay T^8 , wires 161 and 141, winding of relay M^8 , wires 142, 94, 95 and 143 to battery H^F . It will be seen, therefore, that relay M^8 is picked up only when track relay T^8 is open 80 and circuit controller J^8 is closed; in other words, only when a train moving towards the west passes signal S^8 . Relay M^8 is provided with a holding circuit which passes from battery H^F , through wires 134, 135, 136, 85 137 and 138, circuit controller J^8 (with signal in stop position), wires 162, 147 and 148, contact 149 of relay M^8 , wires 150 and 141, winding of relay M^8 , and wires 142, 94, 95 and 143 to battery H^F . This holding circuit is provided with a branch around circuit controller J^8 , which branch passes from wire 137, through wire 163, back point of contact 145 of relay R^8 , and wire 146 to wire 147. The holding circuit is provided 90 with a second branch around circuit controller J , which passes from wire 137 through wire 163, front point of contact 145, reverse polar contact 165 to wire 148. It will be seen, therefore, that whenever 100 relay M^8 is closed, it will remain closed while signal relay R^8 is de-energized and also while the latter relay is energized in reverse direction.

Assuming first, that relay M^8 is open, 105 as shown in the drawing, the circuit for signal relay R^6 is from the right-hand terminal of battery H^A , through wires 97, and 98, normal polar contact 99 of signal relay R^6 , wires 100, 101 and 102, left hand arm of pole-changer P^2 , wire 103, back point of contact 104 of relay M^8 , wire 105, contact 106 of track relay T^2 , wire 107, front point of contact 108 of track relay T^8 , wire 109, winding of relay R^6 , wire 110, front point of contact 111 of track relay T^8 , wires 112, 113, common wire O^3 , wires 113^a, 95, 94 and 93, back point of contact 92 of relay M^8 , wire 91, right arm of pole-changer P^{90} , and wires 90^a, 90 and 115 116 wire 89 to the left hand terminal of battery H^A . Pole-changer P^{90} is in the normal position when signal S^8 indicates proceed, but moves to its reverse position when signal S^8 falls to the caution or stop position. It follows, therefore, that when relay M^8 is open and signal S^8 indicates caution, signal S^6 will also indicate caution. The reason for this double caution indication at the approach to the passing sid- 120 125 130 135 140 145 150 155 160 165 170 175 180 185 190 195 200 205 210 215 220 225 230 235 240 245 250 255 260 ing F is well understood, and requires no explanation in connection with the present application. When relay M^s is closed, the circuit for relay R⁶ is from the right hand 5 terminal of battery H^A, through wires 97, and 98, contact 99, wires 100, 101, 114 and 115, left hand arm of pole-changer P⁴⁵, wire 116, front point of contact 104, and thence through the same circuit as before 10 to the front point of contact 92 of relay M^s, then through wire 117, right hand arm of pole-changer P⁴⁵, and wires 118, 90 and 89 to battery H^A. Pole-changer P⁴⁵ occupies 15 its normal position when signal S^s is in either the proceed or the caution position, but reverses before this signal reaches the stop position. It follows, therefore, that when relay M^s is energized, and signal S^s indicates caution, signal S⁶ will indicate 20 proceed.

The signal relay R⁶ is provided with a local circuit which is supplied with energy from battery H^B, and which circuit is similar in all respects to the local circuit herein- 25 before explained for signal relay R⁴.

The circuits and apparatus associated with the eastbound signals S¹, S³, S⁵ and S⁷, are similar in all respects to the circuits and apparatus which I have explained in detail in connection with the westbound signals.

The operation of the westbound signals is as follows: When a westbound train passes signal S², it opens track relay T⁹, 35 thereby opening at contact 40 the circuit for relay R², so that signal S² moves to the stop position. As the train passes out of sub-section Q—E and into sub-section D—Q, it causes no change in the apparatus, because relay R² is controlled by track relay T⁸ as well as by track relay T⁹. As the train passes signal S⁴, the opening of track relay T⁷ opens at contact 25 the circuits for signal S⁴, so that this signal 40 likewise moves to the stop position. This operation of track relay T⁷ does not, however, de-energize relay R⁴, because the local circuit for this relay is closed through the back points of track relay contacts 73 45 and 76. As soon as the rear end of the train passes out of sub-section D—Q, the consequent closing of track relay T⁸ closes the main circuit for relay R², and inasmuch as signal S⁴ is then in the stop position, 50 the current supplied to this relay by battery H^D is of reverse polarity so that relay R² becomes energized in the reverse direction. The reversal of contact 44 of this relay places battery H^G in circuit with the 55 relay and in series with battery H^D so that the two batteries assist each other in energizing the relay. The energization of relay R² in reverse direction causes signal S² to move to the caution position. When the 60 entire train passes out of sub-section U—D, 65

track relay T⁷ closes, thereby opening the local circuit for signal relay R⁴. This relay then becomes de-energized, because its main circuit is open at contact 71 of track relay T⁶, and so it follows that battery H^D 70 is cut out of the circuit for relay R² and this circuit is closed at point D through the back point of contact 22 of relay R⁴. Relay R² continues to be energized in the reverse direction, however, owing to the 75 supply of current from battery H^G, which battery is now connected to this relay through the reverse point of polar contact 44. The passage of the train into sub-section C—U has no other effect in the control of the westbound signals. As the train enters sub-section N—C, it opens track relay T⁵, but in so far as the westbound signals are concerned this relay merely keeps the circuit for relay R⁴ open. The same 80 thing is true as the train passes out of sub-section N—C and into sub-section B—N. In other words, while the train is at any point between B and D, signal S⁴ is at stop and signal S² at caution. As the train 85 enters sub-section K—B, the opening of track relay T³ opens the circuits for signal S⁶ at contact 164 so that this signal moves to the stop position. Relay R⁶ does not open, however, at this time. As soon as 90 the rear end of the train passes out of sub-section B—N, the main circuit for relay R⁴ becomes closed, so that this relay then becomes energized in the reverse direction, due to the fact that pole-changer P⁶ 95 is reversed. The closing of relay R⁴ closes the caution indication circuit for signal S⁴, so that this signal then moves to the caution position. This movement of signal S⁴ causes pole-changer P⁴ to return to the normal position, whereupon batteries H^D and H^G oppose each other in the circuit for relay R². This relay then opens, but is immediately re-energized from battery H^D, owing to the branch through back contact 100 55 of relay R². Current of normal polarity then being supplied to relay R², the battery H^G is cut out of the circuit of this relay by contact 44, so that the relay is then energized in normal direction from battery H^D. 105 The energization of relay R² in normal direction causes signal S² to return to its proceed position. With the train in sub-section K—B, then, signal S^s is at stop, signal S⁴ at caution and signal S² at proceed. Relay R⁴, is, of course, supplied with current from batteries H^B and H^D in series. As the train passes point K, however, relay R⁶ opens, thereby cutting battery H^B out 110 of this circuit, so that relay R⁴ is then energized in reverse direction by current from battery H^D alone. As the train passes signal S^s, it closes relay M^s, thereby placing relay R⁶ under the control of pole-changer P⁴⁵, and relay R⁶ then becomes energized 115 120 125 130

in reverse direction, owing to the fact that pole-changer P^4 is in reverse position. Signal S^6 consequently moves to the caution position, and the consequent return of 5 pole-changer P^6 to the normal position momentarily places batteries H^B and H^D in opposition in the circuit of relay R^4 , so that this relay opens but is immediately re-energized in normal direction from battery H^B , through the branch connection including back contact 158. Current of normal polarity thus being supplied to relay R^4 , signal S^4 moves to the proceed position. When the rear end of the train passes point 10 Q (right hand end of Fig. 1^a), relay R^8 becomes energized in reverse direction, so that signal S^8 moves to the caution position, and signal S^6 returns to the proceed position because relay R^6 is still under the 15 control of pole-changer P^4 . When the train passes point D , signal S^2 moves to the caution position, so that pole-changer P^2 then causes relay R^8 to become energized in normal direction, whereupon relay M^8 opens 20 and signal S^8 returns to the proceed position. The parts of the apparatus are then restored to the positions in which they are shown in the drawing.

Assuming now that an eastbound train 25 passes over the track, it will be seen that while this train is in any part of the block to the west of siding F , signals S^8 and S^6 both indicate caution, whereas signals S^4 and S^2 both indicate proceed. When the 30 train passes the point corresponding to point Q , relay R^8 is opened so that signal S^8 moves to the stop position, but this does not affect signal S^6 . As soon as the train passes point A , the opening of track relay T^2 opens 35 the circuit for relay R^6 , so that signal S^6 moves to the stop position. The opening of relay R^6 cuts battery H^B out of the circuit for relay R^4 , so that this latter relay opens, and causes signal S^4 to assume the stop position. The 40 opening of relay R^4 cuts the battery H^D out of the circuit for relay R^2 , so that the latter relay opens and causes signal S^2 to assume the stop position. The 45 westbound signals then return to the proceed positions as they are passed by the rear end of the train.

The operation of the apparatus in so far as the eastbound signals are concerned will be understood from the foregoing explanation without detailed discussion.

It will be observed that the circuit for signal relay R^6 includes a contact 50 99 which is operated by signal relay R' and is closed only when the latter relay is energized in the normal direction; similarly, the circuit for signal relay R^4 includes a contact 65 65 which is closed only when signal relay R^8 is energized in normal direction. The reason for this control is as follows: Assuming that these contacts are not included in

the signal relay circuits, it will be seen that if an eastbound train should pass through the block and signal relay R^2 should be left in the open position, a subsequent westbound train entering block A-E would 70 not place signal S^2 at the stop. By including the contact 99 in the circuit for relay R^6 I avoid this possibility. With the circuits as shown, if relay R^8 should remain open after an eastbound train passes 75 through the block, relay R' would remain energized in reverse direction, so that contact 99 would be open, and, consequently, signals S^6 , S^4 and S^2 would all remain in the stop position. Similarly if relay R^5 80 should remain open after the passage of an eastbound train through the block, relay R^8 would be energized in reverse direction, contact 65 would be open and signals S^4 and S^2 would be left in the stop position. Contacts 99 and 65 serve as checks, therefore, on the proper operation of the apparatus.

Although I have herein shown and described only one form of signaling system embodying my invention, it is understood 90 that various changes and modifications may be made therein, within the scope of the appended claims without departing from the spirit and scope of my invention.

Having thus described my invention, what 95 I claim is:

1. A signaling system for single track railways comprising two successive signals S^2 and S^4 , a polarized signal relay R^2 for controlling signal S^2 and a signal relay R^4 100 for controlling signal S^4 ; means controlled by a train moving in the direction in which said signals govern traffic for placing signal S^4 at stop when the train passes such signal but for keeping relay R^4 energized until the train has passed a given distance beyond such signal; a circuit for relay R^2 including a battery at signal S^4 , a front contact of relay R^4 , a pole-changer operated by signal S^4 and a normal polar contact of 105 relay R^2 ; a track circuit between said signals for controlling said relay circuit, a branch for said circuit around the normal polar contact of relay R^2 and including a reverse polar contact of relay R^2 and a battery at signal S^2 which battery assists the first battery to energize relay R^2 in reverse direction, a second branch for said circuit around the front contact of relay R^4 and the battery at signal S^4 and including a 110 back contact of relay R^4 , whereby when the latter relay becomes de-energized relay R^2 continues to be reversely energized by the battery at signal S^2 , and a third branch for said circuit around the normal polar contact of relay R^2 and including a back contact of relay R^2 .

2. A signaling system for single track railways comprising two successive signals S^2 and S^4 , a polarized signal relay R^2 for 115 120 125 130

controlling signal S^2 and a signal relay R^4 for controlling signal S^4 ; means controlled by a train moving in the direction in which said signals govern traffic for placing signal S^4 at stop when the train passes the signal but for keeping relay R^4 energized until the train passes a given distance beyond such signal; a circuit for relay R^2 including a normal polar contact thereof, a pole-changer operated by signal S^4 and a battery at signal S^4 ; means controlled by relay R^4 when de-energized for cutting said battery out of said circuit, a branch for said circuit around the normal polar contact and including a reverse polar contact of relay R^2 and a second battery, and a third branch for said circuit around said polar contacts and said second battery and including a back contact of relay R^2 and a resistance.

3. A signaling system for single track railways comprising two successive signals S^2 and S^4 , a polarized signal relay R^2 for controlling signal S^2 and a signal relay R^4 for controlling signal S^4 ; a circuit for relay R^2 including a normal polar contact thereof, a pole-changer operated by signal S^4 and a battery at signal S^4 ; means controlled by relay R^4 when de-energized for cutting said battery out of said circuit, a branch for said circuit around the normal polar contact of relay R^2 and including a reverse polar contact of relay R^2 and a second battery, and a third branch for said circuit around said polar contacts and said second battery and including a back contact of relay R^2 .

4. A signaling system for single track railways comprising two successive signals S^2 and S^4 , a polarized signal relay R^2 for controlling signal S^2 and a signal relay R^4 for controlling signal S^4 ; means controlled by a train moving in the direction in which said signals govern traffic for placing signal S^4 at stop when the train passes such signal and for subsequently de-energizing relay R^4 when the train passes a certain distance beyond such signal, a battery adjacent each signal, means for normally supplying current of normal polarity to relay R^2 from the battery at signal S^4 , means for reversing the polarity of the current supplied to relay R^2 when signal S^4 is at stop and relay R^4 is energized, means for including the battery at signal S^2 in the circuit for relay R^2 when the latter relay responds to such reversal, means controlled by relay R^4 when de-energized for cutting the adjacent battery out of the circuit for relay R^2 whereby the latter relay then remains energized in reverse direction by the other battery, and means controlled by relay R^2 when de-energized for cutting the adjacent battery out of the circuit for such relay.

5. A signaling system for single track

railways comprising two successive signals S^2 and S^4 , a polarized signal relay R^2 for controlling signal S^2 and a signal relay R^4 for controlling signal S^4 ; means controlled by a train moving in the direction in which said signals govern traffic for placing signal S^4 at stop when the train passes such signal and for subsequently de-energizing relay R^4 when the train passes a certain distance beyond such signal, a battery adjacent each signal, a circuit for relay R^2 including a pole-changer operated by signal S^4 , means controlled by relay R^4 for cutting the adjacent battery in or out of said circuit according as the relay is energized or de-energized, means controlled by relay R^2 for cutting the adjacent battery in or out of said circuit according as the relay is energized in reverse or normal direction, and means controlled by relay R^2 for cutting the adjacent battery out of said circuit when the relay becomes de-energized after having been energized in reverse direction.

6. A signaling system for single railways comprising a signal, a signal relay for said signal, a track circuit extending in advance of said signal, and including a track relay, means for controlling said signal by both of said relays, a circuit for said signal relay controlled by front contacts of said track relay and by other means located in advance of said track circuit, a local circuit for said signal relay including back contacts of said track relay and a circuit controller operated by said signal and closed when the signal indicates proceed and caution, but not when it indicates stop, and a branch for said local circuit around said circuit controller and including a front contact of said signal relay.

7. A signaling system for single track railways comprising a signal, a signal relay for said signal, a track circuit extending in advance of said signal, and including a track relay, means for controlling said signal by both of said relays, a circuit for said signal relay controlled by front contacts of said track relay and by other means located in advance of said track circuit, a local circuit for said signal relay including back contacts of said track relay and a circuit controller operated by said signal and closed when the signal indicates proceed and caution, but not when it indicates stop, and a branch for said local circuit around said circuit controller and including a front contact of said signal relay, and a second signal in the rear of the first and controlled in part by said signal relay.

8. A signaling system for single track railways comprising a signal, a signal relay for said signal, a track circuit extending in advance of said signal, and including a track relay, means for controlling said signal by both of said relays, a circuit for said signal

relay controlled by front contacts of said track relay and by other means located in advance of said track circuit, a local circuit for said signal relay including back contacts 5 of said track relay and a front contact of the signal relay, and a second signal in the rear of the first and controlled in part by said signal relay.

9. A signaling system for single track rail-
10 ways comprising a signal, a signal relay for said signal, a plurality of track circuits located in advance of said signal and each including a track relay, means for controlling said signal by said signal relay and by the 15 relay for the first track circuit in advance of the signal, means for controlling said signal relay by all of said track circuits, means for keeping said signal relay energized until a train moving in the direction in which said 20 signal governs traffic leaves said first track circuit but for preventing energization of such relay when a train moving in the other direction occupies said first track circuit, and a second signal in the rear of the first 25 and controlled in part by said signal relay.

10. A signaling system for single track railways comprising a signal, a signal relay for said signal, a plurality of track circuits located in advance of said signal and each 30 including a track relay, means for controlling said signal by said signal relay and by the relay for the first track circuit in advance of the signal, a main circuit for said signal relay controlled by the track relay 35 for each of said track circuits and opened when any track relay is deenergized, an auxiliary circuit for said signal relay closed while a train moving in the direction in which said signal governs traffic occupies 40 said first track circuit but not when a train moves in the other direction, and a second signal in the rear of the first and controlled in part by said signal relay.

11. A signaling system for railways comprising a signal, a signal relay for controlling said signal, means controlled by a train moving in the direction in which said signal governs traffic for placing said signal at stop when the train passes the signal and for subsequently deenergizing said relay when the train passes a certain point in advance of the signal, and a second signal in the rear of the first signal and controlled in part by said 50 relay.

12. A signaling system for railways comprising a signal, a signal relay for controlling said signal, means controlled by a train moving in the direction in which said signal governs traffic for placing said signal at stop when the train passes the signal and for subsequently de-energizing said relay when the train passes a certain point in advance of the signal, said means being ineffective to energize the relay during the passage 60 of a train in the other direction until the

train has passed the signal, and a second signal in the rear of the first and controlled in part by said relay.

13. A railway signaling system comprising two signals governing traffic in one direction along a single track, a signal relay for each signal, means for controlling the relay for the rear signal by the relay for the forward signal, track circuits for controlling said relays, a signal for governing traffic in 70 the other direction along said track, a signal relay for the last-mentioned signal, and a circuit for the last-mentioned signal relay including a contact of one of the first-mentioned relays. 80

14. In combination, a stretch of single track over which traffic moves in both directions, signals located at intervals for governing traffic along said stretch in one direction, a polarized signal relay for each signal, 85 a circuit for each signal relay including a pole-changer operated by the signal next in advance, a source of current for each signal relay circuit located adjacent the next signal in advance; means controlled by each 90 signal relay for connecting the adjacent source of current with the circuit for the relay in the rear, or for placing the latter relay on short circuit, according as the former relay is closed or open; track circuits for the 95 stretch controlling said signal relay circuits, means for controlling each signal by the corresponding signal relay and by the first track circuit in advance of the signal, means for keeping each signal relay closed until 100 after a train passing the corresponding signal has placed such signal at stop and so reversed the polarity of the current supplied to the signal relay next in the rear, and a branch for each signal relay circuit including the adjacent source of current and a contact which is closed when the relay is 105 energized in reverse direction.

15. In combination, a stretch of single track over which traffic moves in both directions, signals located at intervals for governing traffic along said stretch in one direction, a polarized signal relay for each signal, means for controlling each relay by the relay next in advance and by a pole-changer 110 operated by the signal next in advance, means controlled by a train moving in said direction for placing each signal at stop as it passes the signal and for opening the corresponding relay after the signal has been 115 placed at stop, and auxiliary means for energizing each relay when the signal in advance is at stop.

16. In combination, a stretch of single track over which traffic moves in both directions, signals located at intervals for governing traffic along said stretch in one direction, a polarized signal relay for each signal, track circuits for the stretch including 125 track relays, means for controlling each sig- 130

nal by the corresponding signal relay and by the track relay for the first track circuit in advance of the signal, means for controlling each signal relay by the track circuits 5 in advance of the corresponding signal but for keeping such relay closed until a train moving in the said direction has placed the signal at stop; means controlled by each signal relay when closed for supplying current to 10 the signal relay in the rear through a pole-changer operated by the advance signal, and for discontinuing such supply and placing the relay in the rear on short circuit when the advance relay is open; and 15 auxiliary means for supplying current to

each signal relay when the same is energized in reverse direction and the signal relay next in advance is open.

17. A railway signaling system comprising 20 a signal governing traffic in one direction along a single track, a relay for controlling said signal, a second and a third signal governing traffic in the other direction along said track, a second and a third relay for controlling said second and third signals respectively, and a circuit for said third relay including contacts of said first and second relays.

In testimony whereof I affix my signature.

CHARLES H. LAY.
